UNITED STATES PATENT OFFICE.

MICHAEL FRANK BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

LIQUID-APPLYING DEVICE.

1,090,196.

Specification of Letters Patent. Patented Mar. 17, 1914.

Application filed January 31, 1906. Serial No. 298,809.

To all whom it may concern:

Be it known that I, MICHAEL FRANK BROGAN, a citizen of the United States, residing at Lawrence, in the county of Essex and Commonwealth of Massachusetts, have invented certain Improvements in Liquid-Applying Devices, of which the following description, in connection with the accompanying drawings, is a specification, like reference characters on the drawings indicating like parts in the several figures.

This invention relates to a liquid applying device and is herein illustrated in connection with a brush for use in machines for applying cement to parts of boots and shoes.

It is customary to apply cement to the channels of the soles of shoes by presenting the sole of the shoe to a rotating member which carries a coating of cement. It has been found to be desirable to use a bristle brush the bristles of which are fastened in a holder of cheap material such as wood and to discard the holder after the bristles have become worn rather than to make the holder of a more expensive material such as metal and to refill the holder with new bristles. A wooden holder, however, is liable to swell or warp on account of the action of the liquid cement, and in order to provide for this characteristic it is desirable that the holder be loosely confined.

To this end the present invention comprises a hub, a cement applying member of expandable material mounted thereon, means for loosely confining said member in place, and means for rotating said member. This and other features of the invention, including certain details of construction and combinations of parts will be described in connection with an illustrated device and pointed out in the appended claims.

Referring now to the accompanying drawings,—Figure 1 is a vertical sectional view taken transversely of the axis of rotation of a device in which the present invention is embodied; Fig. 2 is a vertical sectional view taken longitudinally of said axis, the rotary shaft being shown in full lines; Fig. 3 is a view similar to Fig. 2 but showing a modification.

Referring first to Figs. 1 and 2 of the drawings, cement is supplied from any suitable reservoir or tank, from which it is led by any convenient means, as a conduit 12 to

the cement-applying member which is mounted in such manner that a shoe or other article to be cemented may be conveniently presented thereto. The applying member is herein shown as a circular brush preferably composed of a series of knots of bristles but obviously any suitable material may be substituted for the bristles, or any other means capable of performing the required function may be employed. This brush is suitably secured to one end of a rotary shaft 16 conveniently located with respect to the opening from conduit 12. The preferred manner of constructing the brush is to wire or otherwise secure the knots of bristles about the periphery of a body portion in the form of an annulus 18 which, as it is discarded when the bristles are worn out, is preferably of some inexpensive material such as wood. Thus the acting portion of the applying member has a support independent of the rotating hub 20 on which it is mounted. Although wood is a preferable selection for the material from which annulus 18 is made, an objection thereto is that when moist it will expand and warp, thus tending to throw any device used for securing it on hub 20 out of alignment which is undesirable in this machine. Therefore the annulus, if of wood or a similar material, must be mounted so as to allow for expansion. In the construction shown in Figs. 1 and 2 the hub 20 is provided with suitable devices, preferably situated adjacent the cement-applying member, for securing said member against lateral displacement, here shown as a pair of flanges 22 and 24. The inner flange 22 is preferably cast integral with the hub, the outer flange 24 being made removable therefrom. Flange 22 is provided with a peripheral lip 23 adapted to overlap annulus 18 and bring the flange edge nearer the brush, its peripheral face being preferably beveled as shown at 25. Flange 24 is provided with a peripheral lip and beveled face in a similar manner to flange 22. Hub 20 is provided with an annular rabbet 26 in which flange 24 rests, abutting against the shoulder formed thereby. The hub 20 is so proportioned that the distance from the inner face of flange 22 to the shoulder formed by the rabbet 26 is slightly greater than the width of annulus 18. With this construction, although the annulus is held securely in place, sufficient space is left between the inner faces 105 of flange 22 to the shoulder formed by the rabbet 26 to the width of annulus 18. With this construction, although the annulus is held securely in place, sufficient space is left between the inner faces 110 of flange 22 to the shoulder formed by the rabbet 26 to the width of annulus 18.

of the flanges and the side of the annulus to allow for the expansion or warping of the latter when a material in which this is likely to occur is used. Any convenient means may be used to prevent rotation of annulus 18 on hub 20, an efficient arrangement comprising a slot or groove 19 in the annulus adapted to register with a pin 28 passed radially through lip 23 of flange 22. The assembled hub and brush are secured to shaft 16 in any convenient manner as by a locking screw 30 threaded into the end of said shaft and holding the hub between collars 32 and 34 on the shaft and screw respectively.

15 The construction of Fig. 3 is similar to that of Fig. 2 in all respects with the exception that rabbet 26' on hub 20' is provided with screw-threads 27, removable flange 24' being also screw-threaded as at 29, the two fitting together. It is thus seen that flange 24' may be screwed up tight against annulus 18', when said annulus is composed of moisture-proof material, and then locked in position, or it may be adjusted so as to allow 25 for a slight clearance when the annulus is composed of wood or a similar material.

Although the invention has been set forth in connection with a machine for applying cement to shoes it should be understood that 30 this has been done for purposes of illustration

only, and that the invention is not limited in the scope of its application to the particular machine shown and described.

Having thus described my invention, I claim as new and desire to secure by Letters 33 Patent of the United States:

1. In a cementing machine, a hub, a cement applying member of expandible material mounted thereon, means for loosely confining said member in place, and means for 40 rotating said member.

2. In a cementing machine, the combination of a hub, a brush comprising bristles set in an annulus of less width than that of the hub and holding plates arranged at each 45 side of the brush, said plates having annular faces arranged to contact with the bristles.

3. A device of the class described having a bristle holder of expandible material, plates for loosely confining said holder in 50 place and means for connecting said holder with one of said plates to cause it to be rotated therewith.

In testimony whereof I have signed my name to this specification in the presence of 55 two subscribing witnesses.

M. FRANK BROGAN.
